UNITED STATES PATENT OFFICE.

WILLIAM F. BROWN, OF CLINTON, INDIANA, ASSIGNOR OF ONE-HALF TO W. F. DECKER, OF CLINTON, INDIANA.

SWITCH.

1,160,039.

Specification of Letters Patent.

Patented Nov. 9, 1915.

Application filed May 11, 1915. Serial No. 27,367.

To all whom it may concern:

Be it known that I, WILLIAM F. BROWN, citizen of the United States, residing at Clinton, in the county of Vermilion and 5 State of Indiana, have invented certain new and useful Improvements in Switches, of which the following is a specification.

The present invention appertains to improvements in switches, and in particular to 10 the joint connections for switch rails, the object in view being to provide a simple interlocking arrangement to enable ready application or displacement of the switch rails for repair or other purposes.

15 In essential characteristics the invention consists, in combination with a main track rail, of a seat or chair connected thereto and comprising a socket to receive a cross head locking member carried by the switch 20 rail, whereby to effect attachment or displacement of the latter it is requisite only that the rail be turned to substantially right angles to the main track rail.

In addition to the foregoing it is comprehended to provide special pivot means for 25 maintaining proper position of the pivoted end of the switch rail in the seat hereinbefore referred to.

These and such other objects as may hereinafter appear are attained by the novel construction, combination, and arrangement of parts to be hereinafter specifically described and claimed.

Reference will now be had to the accompanying drawing forming a part of this specification, wherein:

Figure 1 is a plan view of a switch construction embodying my invention, certain parts being broken away to show more 35 clearly the details of construction. Fig. 2 is a transverse sectional view taken about on the line 2—2 of Fig. 1. Fig. 3 is a sectional view taken on the line 3—3 of Fig. 1. Fig. 4 is a horizontal sectional view taken on the 40 line 4—4 of Fig. 5. Fig. 5 is a sectional view taken on the line 5—5 of Fig. 2. Fig. 6 is a perspective view of a switch rail forming an essential feature of this invention.

Referring to the drawings and specifically 45 describing this apparatus, the numeral 1 designates main track rails and 2 the siding rails. In carrying out my invention I preferentially employ a split switch of well known type and consisting of corresponding switch

rails 3, 3, one of which coacts with one of 55 the main track rails and the other coacting with one of the siding rails as best disclosed by reference to Fig. 1. These switch rails have pivotal movement, as will be herein-after more clearly set forth, and are adapted 60 to be actuated in any well known manner, as by means of a switch lever 4 located adjacent the main track at a convenient point, said lever being connected by a rod 5 to a cam plate 6 disposed at one side of the track 65 upon tie extensions 7 and preferably within a protective housing or casing 8 having a hinged cover 8'. The plate 6 is provided approximately centrally thereof with a diagonal slot 9 into which is interlockingly received the head 10 carried by a transverse bar 11, which latter in turn is connected at its opposite end to a connecting bar or link 12 pivotally secured at its extremities to the respective switch rails 3. It will be 70 apparent to those skilled in the art to which this invention refers that movement of the lever 4 backwardly and forwardly will impart cam action through the plate 6 to the bar 11 which will actuate the switch rails 80 3 for moving them pivotally to effect the proper coöperation of the respective switch rails with either the main or siding track rails. The pivotal connections 12^a and 12^b for the link 12 are detachable and when removed the switch rails are capable of being 85 displaced from their operative connections with the respective track rails as will be described more clearly hereinafter. The forward or pointed end of each switch rail rests 90 upon supports or plates 13 which are secured to a tie intermediate the track rails and each comprises a cam surface 14 on which the switch rail rests, as hereinbefore mentioned. This surface as shown more particularly in 95 Fig. 2 is inclined and as the switch rail is moved the pointed end thereof is brought up into proper alinement with the surface of its respective coöperating track rail where it is rigidly held for performing its proper function of deflecting movement of a train from one track to another. It will be apparent that the members 13 are also fastening members for holding the rails in place and thereby serve a dual function.

The switch rail joints which comprise an essential feature of this apparatus are both similarly constructed and one only of the

same will be described, the same reference characters, however, appertaining to the same parts in each of these joint members. The switch joint comprises a socket 16, which 5 is shallow and of course hollow, being formed with overhanging spaced flanges 17 which provide an elongated opening 18 at the top thereof. This opening 18 is in alignment with the track rail to which the joint 10 is connected and the socket is adapted to receive the cross head 19 formed on the switch rail 3 at its pivoted end, said head or plate 19 being spaced by the shank 20 from the body portion of the switch rail and said 15 rail being suitably cut away as indicated at 21 so as to permit of pivotal movement of this member in the socket. It will be noted that the socket is formed with spaced fish plate extensions 22 which are bolted or 20 otherwise detachably secured to the track rail by fastening members 23. It will be obvious that this peculiar joint does not require any special construction of track rail with which it co-operates and this is an im- 25 portant advantage of my construction. In the attachment or displacement of the switch rail from its socket it is necessary that the rail be turned at substantially right angles to the track rail to which the socket is con- 30 nected so as to bring the head 19 in registry with the opening 18, it being understood, of course, that the connecting member for the link 12 is removed to permit of this operation. The head 19 obviously forms a lock- 35 ing member for the switch rail connection and as particularly shown in Fig. 3 of the drawing the chair or socket is formed centrally thereof with an upstanding pivot stud 24 which is received in a recess formed in 40 the central portion of the cross head 19 as designated 25. This pivotal connection prevents tendency of displacement of the switch rail under stresses from the socket as well as eliminates likelihood of binding of the 45 head in its seat. The spaced flanges 17 of the socket or chair 16 are designed to constitute stop means for limiting movement at the pivoted end of the switch rail, the space 50 between the flanges allowing said rail to move at the pointed end a distance less than the length of its supporting cam.

It will be obvious that slight changes may readily be made in the details of construction and arrangement of the parts hereinbefore described without departing from the spirit of the invention and within the scope of the claims hereto appended.

Having thus described the invention, what is claimed is:—

1. In combination, a track rail, a switch rail coacting therewith, a switch joint comprising a chair adapted to interlockingly receive the pivot end of the switch rail, said joint being formed with fish plate extensions co-operating with the track rail, and fastening means for securing said extensions to the track rail.

2. In combination, a track rail, a switch rail coacting therewith, a switch joint connected to the track rail and having a socket having an opening extending in alignment with the track rail, and an elongated head projecting from beneath the switch rail at an angle thereto adapted to be received in said socket upon registry of the cross head with the opening aforesaid.

3. In combination, a track rail, a switch rail coacting therewith, a switch joint having a socket, fish plate extensions for connecting said joint to the track rail, connecting members for securing the fish plate extensions to the track rail, and a locking member carried by the switch rail adapted to be received in the socket.

4. In combination, a track rail, a switch rail coacting therewith, a switch joint having a socket, fish plate extensions for connecting said joint to the track rail, connecting members for securing the fish plate extensions to the track rail, a locking member carried by the switch rail adapted to be received in the socket, and pivot means formed on said joint for preventing displacement of the switch rail in the socket aforesaid.

5. In combination, a track rail, a switch rail coacting therewith, a switch joint comprising a chair to receive the pivot end of said switch rail, means for securing said joint to the track rail, and a flange formed on said chair at either side of the switch rail for limiting pivotal movement of said switch rail.

6. In combination, a track rail, a switch rail coacting therewith, a switch joint comprising a chair to receive the pivot end of said switch rail, means for securing said joint to the track rail, spaced flanges formed on said chair, a cross head on said switch rail seated in said chair, and a pivot member formed on said chair, the switch rail aforesaid having a recess to receive said pivot member.

In testimony whereof I affix my signature.
WILLIAM F. BROWN.
